UNITED STATES PATENT OFFICE.

EMIL R. CRECELIUS, OF PROVIDENCE, RHODE ISLAND, ASSIGNOR TO ARNOLD C. MESSLER, OF PAWTUCKET, RHODE ISLAND.

PIN.

No. 896,199.

Specification of Letters Patent.

Patented Aug. 18, 1908.

Application filed February 25, 1908. Serial No. 417,685.

To all whom it may concern:

Be it known that I, EMIL R. CRECELIUS, a citizen of the United States, residing at Providence, in the county of Providence and 5 State of Rhode Island, have invented certain new and useful Improvements in Pins, of which the following is a specification.

My invention relates to that class of pins commonly known as cuff pins, struck up from 10 a blank of sheet metal to form a hollow body; and has for its essential objects, besides the ends commonly sought in this class of pins, a finished appearance without the aid of external burnishing or polishing; an improved 15 and inexpensive fulcruming means for the pin-tongue head; and means for retaining the pivot pin against longitudinal play. Heretofore the fulcruming means in this 20 class of pins have consisted of independent pieces which after some use become detached; or an inwardly folded finger which crimps the stock of the pin in bending and in practice forms an uncertain and non uniform bearing for the pin tongue head.

25 To the end of securing the advantages and avoiding the disadvantages above enumerated, my invention consists in the novel construction and combination of parts herein-after set forth, and illustrated in the accompanying drawings, wherein

Figure 1 is a plan view of the pin blank. Fig. 2, a plan elevation of the same after the first operation. Fig. 3, a section on line 3, 3 of Fig. 2. Figs. 4 and 5, sections on lines 4, 4 35 and 5, 5 respectively of Fig. 3. Fig. 6, a plan of the pin after the second operation. Fig. 7, a section of line 7, 7 of Fig. 6. Figs. 8 and 9, sections on lines 8, 8 and 9, 9 respectively of Fig. 7. Fig. 10, a side elevation of the complete pin and its parts mounted, and Fig. 11, a transverse section of the same on line 11, 11 of Fig. 10.

Like reference letters indicate like parts throughout the views.

45 My pin is formed as follows: A blank or planchet is cut from a sheet of metal, shaped as shown in Fig. 1, comprising a body, *a*, lateral ears, *b*, adjacent one end, and a lateral projection, *c*, adjacent the other end. By 50 suitable dies the blank is struck into the form shown in Fig. 2, consisting of an ob-

long, cupped body, *a*, with upwardly inclined blank ears, *b*, and projection, *c*. The incomplete pin is next subjected to the action of compression dies and punches, whereby 55 the material in the walls of the body near and at their ends is compressed, forming solid integral bearing or fulcrum blocks, *d* and *d'*, in opposite ends of the body, *a*, whose top surfaces are preferably slightly inclined towards 60 the center of the pin body. The action of the punches is to form cavities, *e*, in ears, *d*. The edge of the cup walls are by the tools referred to rounded as at *f*, to avoid cutting edges and give a finished appearance to that 65 part of the body. The parts as described are shown in Figs. 6, 7, 8 and 9. The pin is completed by bending the projection, *c*, to form a catch and bending the ears upwardly, so that the cavities, *e*, shall receive the ends of the 70 pivot pin, *g*, upon which is mounted the pin tongue, *h*, the forward portion, *k*, of whose head, *l*, bears down upon the integral block, *d*. The pivot pin is incapable of any slipping or longitudinal movement in the ears, and 75 the bearing portion, *d*, is stable and immovable. The downward inclination of the upper face of the bearing block brings the bearing point of the leg or head *k* below the plane of the side walls, preventing the accidental 80 pinching of the lace or other fabric; also permits the axis of the pin tongue to approach the plane of the body *a*, lessening the rocking tendency of the device after engagement.

What I claim is,

1. An article of manufacture comprising a pin formed of sheet metal bent to form a cup shaped oblong body, a block in the end of the body integral with the walls of the body, and integral catch and ears.

2. An article of manufacture comprising a pin formed of sheet metal bent to form a cup shaped oblong body with the edges of the cup walls rounded, a fulcruming block in one end of the body integral therewith and compressed between adjacent walls thereof, an integral catch, and integral ears.

3. A cuff-pin comprising a cup-shaped oblong body provided with a bearing block in one of its ends formed by compressing the adjacent walls of the body and having its upper surface downwardly inclined toward the cen-

ter, and ears and a catch all integral with the walls.

4. A cuff-pin formed of plated material and comprising a cup-shaped oblong body provided with a bearing block in one of its ends integral with the adjacent walls of the body, ears integral with the walls adjacent the bearing block, and a catch integral with

the wall of the body, the marginal walls having their edges rounded. 10

In testimony whereof I have affixed my signature in presence of two witnesses.

EMIL R. CRECELIUS.

Witnesses:

HORATIO E. BELLOW,
JOSEPH E. BURNS.
